UNITED STATES PATENT OFFICE.

THOMAS F. WEBSTER, OF SEWICKLEY, PENNSYLVANIA, ASSIGNOR TO LINK-BELT COMPANY, OF CHICAGO, ILLINOIS, A CORPORATION OF ILLINOIS.

SCREENING-CONVEYER.

1,142,648.

Specification of Letters Patent.

Patented June 8, 1915.

Application filed January 27, 1912. Serial No. 673,708.

To all whom it may concern:

Be it known that I, THOMAS F. WEBSTER, a citizen of the United States, residing at Sewickley, county of Allegheny, State of 5 Pennsylvania, have invented certain Improvements in Screening-Conveyers, of which the following is a specification.

One object of my invention is to provide means for screening coal and like material 10 as it is conveyed from one point to another.

A further object of the invention is to provide a screen in which a bucket conveyer is used, the screen being so located that the material to be screened will flow from the 15 bucket by gravity over the screen, and the particles not passing through the screen will be picked up again by the bucket and conveyed to a discharge point.

In the accompanying drawing: Figure 1, 20 is a longitudinal sectional view of a conveying and screening apparatus illustrating my invention; Fig. 2, is a plan view of a conveying and screening apparatus; and Fig. 3, is a view of a modification of the invention.

25 A is an endless conveyer consisting of chains *a* to which are attached buckets *b*. These buckets are of the form illustrated in Fig. 1, and are used for elevating, as well as conveying, the material in a horizontal plane 30 over a trough.

B' are the head wheels around which the upper run of the conveyer passes, and D is the horizontal portion of the trough or bed over which the conveyer is guided.

35 D' is an inclined portion of the bed being arranged at such an angle that the coal or like material will flow out of the buckets by gravity onto the trough.

d, d are bars which are spaced a given distance apart to form a screen so that as the coal flows down the portion D' of the trough, the small particles of coal will pass through the screen, while the larger particles will be retained by the bars and when they flow to the lower portion of the trough, where it changes angle, the bucket *b* will pick up the larger portions of the coal and convey them to a discharge point.

40 At intervals in the horizontal portion of the trough are openings *e* closed by suitable doors *E* so that when one of these doors is open the coal will pass through the opening and fall either into the bin directly below it or be guided by troughs to any suitable 45 discharge point. The screenings accumulate

in the bin *G* directly under the screen *d* in the present instance, although there may be a trough arranged under the screens to carry the screenings to any point desired. The coal or other material is elevated by the conveyer from any point as shown in the drawings, and as it passes over the head wheel B it is discharged onto the screen.

In Fig. 3, I have shown a modification in which the trough terminates at the end of the inclined screen portion so that the coal is discharged from the end of the screen into a suitable bin *I* at the point *x*, without the bucket again picking up the material, as in Fig. 1.

While I prefer to use the particular form of bucket illustrated in Fig. 1, the shape or design of the bucket may be modified to meet certain conditions. The bucket must, however, be such that the material can readily flow therefrom onto the screen and can be picked up again by the bucket after passing the screen. The angle of the screen portion of the trough must in all cases be greater than the angle of repose of the material, so that the material will flow down the trough as soon as it is discharged from the bucket; the balance of the trough can be either horizontal, as shown, or at a slight angle, which will not allow the material to rapidly pile 80 against the back of the preceding bucket.

I claim:

1. The combination, in means for screening coal and like granular material, of a screen arranged on an incline greater than the angle of repose of the material being screened, and a continuously moving bucket conveyer arranged to convey the material to the top of the inclined screen and to travel downwardly over the screen whereby the material may be wholly discharged from each bucket at the upper end of the screen and flow downwardly over the screen in advance of the moving buckets which lift the same.

2. The combination, in means for screening coal and like granular material, of a trough having a screen portion arranged on an incline greater than the angle of repose of the material being screened, and a lower portion at a lesser angle, and a continuously moving bucket conveyer arranged to convey the material to the top of the screen and to travel downwardly over the screen whereby the material may be wholly discharged from 110

each bucket at the upper end of the screen and flow over the screen in advance of the moving buckets which lifted the same; the lower portion of the screen structure serving 5 to retard the flow of the material to allow the buckets to again take up the screened material and carry it to a discharge point.

In testimony whereof, I have signed my name to this specification, in the presence of two subscribing witnesses.

THOMAS F. WEBSTER.
